CLAIM

The ornamental design for a meridian thermotherapy apparatus, as shown and described.

DESCRIPTION

FIG. 1 is a perspective view of a meridian thermotherapy apparatus embodying the new design;

FIG. 2 is a front view thereof;

FIG. 3 is a back view thereof;

FIG. 4 is a side view thereof;

FIG. 5 is another side view thereof;

FIG. 6 is a bottom view thereof; and,

FIG. 7 is a top view thereof.

The broken lines in the drawings show portions of the meridian thermotherapy apparatus that form no part of the claimed design.
